DESIGN FOR A GRILLE-GUARDED FRONTAL PANEL FOR AUTOMOBILE RADIATOR SHELLS

Lee B. Green, Lakewood, Ohio, assignor to The
Globe Machine & Stamping Company, Cleve-
land, Ohio, a corporation of Ohio

Application July 13, 1934, Serial No. 52,571

Term of patent 3½ years

To all whom it may concern:

Be it known that I, LEE B. GREEN, a citizen of the United States, residing at Lakewood, in the county of Cuyahoga and State of Ohio, have invented a new, original, and ornamental Design for a Grille-Guarded Frontal Panel for Automobile Radiator Shells, of which the following is a specification, reference being had to the accompanying drawing, forming part thereof.

Fig. 1 is a perspective view of a grille-guarded frontal panel for an automobile radiator shell embodying my invention.

Fig. 2 is a section taken along line 2—2 of Fig. 1.

Fig. 3 is an enlarged front elevation of the upper portion of the grille-guarded frontal panel.

I claim:

The ornamental design for a grille-guarded frontal panel for an automobile radiator shell, substantially as shown.

LEE B. GREEN.
